M. W. HOUSE.
ELECTRIC BATH.

No. 38,389.

Patented May 5, 1863.

Inventor.
Mark W. Hause,

UNITED STATES PATENT OFFICE.

MARK W. HOUSE, OF CLEVELAND, OHIO.

IMPROVEMENT IN ELECTRIC BATHS.

Specification forming part of Letters Patent No. 38,389, dated May 5, 1863.

To all whom it may concern:

Be it known that I, MARK W. HOUSE, of Cleveland, in the county of Cuyahoga and State of Ohio, have invented new and useful Improvements in Electric Baths; and I do hereby declare that the following is a full and complete description of the construction of the same, reference being had to the accompanying drawings, making part of this specification, in which—

Figure 1 is a perspective view, and Fig. 2 is a view, of the under side of the tray.

The nature of my invention relates, first, to constituting the head electrode the terminus of two batteries, which may receive the positive (+) and negative (—) from either of the batteries or instruments, or both of the positives from two distinct batteries or instruments, or both negative currents from two distinct batteries or instruments, thus completing a double current through a single electrode, while the opposite poles of the batteries respectively terminate in traversing electrodes upon the sides of the tub, thus completing the circuit of either or both of the batteries or induced currents through any conducting medium placed between the connected electrodes.

My invention relates, second, to placing conductors along the sides of the tub, as described, and attaching thereto traversing electrodes, as and for the purpose hereinafter set forth.

My invention relates, third, to such an arrangement of traversing electrodes that two independent sets of currents can be worked at the same time in the same direction or in opposite directions, either longitudinally, transversely, or diagonally through the tub.

My invention relates, fourth, to working a primary uninterrupted current in connection with an induced interrupted current, either or both of which may be local or general, as hereinafter specified.

My invention relates, fifth, to an adjustable head electrode, which can be enlarged or diminished at pleasure for the purpose of diffusing or concentrating the electrical currents, as described in the following specification.

The bath-tub A may be made of any suitable material, in length about six feet, in width about two feet, and in depth about eighteen

inches. It may be elevated upon legs so that the top is about three feet from the floor. Both the interior and exterior should be thoroughly painted. Within this tub is placed the basket B. (Shown also in Fig. 2.) This may be made of open-work, and of the same material as cane-bottom chair-seats, upon a light frame, the head end, B', being inclined upward for supporting the head of the patient whose body lies in this basket while taking a bath.

The basket can be removed at pleasure for the purpose of cleaning the tub.

To the under side of the inclined part B' of the basket, I attach the head electrode, C, consisting of two or more plates, so arranged and connected that they can slide upon each other, and thus be extended, as shown in Fig. 2, or contracted to the limits of one plate for the purpose of diffusing or concentrating the action as desired.

D represents a conductor that connects with the head electrode, C, the opposite end of which conductor is secured to the head of the tub by a binding-screw, E, which I place upon the tub for convenience. Any other position would answer the purpose. To this binding-screw is attached two switches, F F', for the purpose of completing or breaking the electrical circuits, as hereinafter stated.

G H I represent three conductors. The conductor G terminates in the button of the switch F. The conductor H passes into the tub and along the back side, as shown at H', and upon this conductor is placed traversing electrode J, forming constantly a contact therewith. This electrode J consists of a plate of thin metal about six inches wide, and long enough to reach the fluid constituting the bath. The conductor I passes down into the tub and runs along the inside of the front, as shown by the dotted line I. Upon this conductor is placed the electrode K, whose position is indicated by the dotted lines. This electrode is constructed like that shown at J, and in the same manner forms a contact with its conductor. Both of these electrodes, as well as the others hereinafter described, can traverse the whole length of their respective conductors and be caused to pass and repass each other at pleasure. The conductors H and I can be united to separate poles of the battery or electrical in-

strument, thus completing a circuit through the electrodes J and K, either transversely or diagonally through the tub; or the conductors H and I can be united, making one pole, as shown at L, and thus form contact with either pole of the battery or instrument, while the circuit in this case is completed through the conductor G and head electrode, C.

M represents a conductor leading from a second battery or instrument, and forms contact with the button of the switch F'.

N represents a conductor leading from the same (second) battery and instrument, and runs along the inside of the tub, as shown at N', and upon which slides the electrode P.

O represents a conductor leading from the battery or instrument No. 2, and runs along the inside of the front of the tub, as indicated by the dotted line O', and upon which slides the electrode Q.

The conductors N and O may be united at R in the same manner as previously shown in relation to conductors H and I; or they may be used as positive and negative, as in the case of H and I. It is hence evident that a number of different combinations can be effected between the conductors G H I and M N O, not necessary here to particularize, except as hereinafter stated.

The operation of this apparatus is as follows: If I wish to pass a general direct interrupted current through the patient I make the head electrode, C, positive (+) and the traversing electrodes J and K negative (-), placing them near the foot of the tub. If an inverse current is required (as in many cases of palsy) the polarity of the current terminating in the head and traversing electrodes should be reversed. Transverse or diagonal interrupted currents can be passed through the patient by cutting off the current in the head electrode, C, by switch F, and making H and I and the electrodes J and K oppositely electric. The direction of the current would depend upon the nature of the disease and the effect to be gained by its use. I also pass uninterrupted primary cur-

rents through the patient at the same time that the induced interrupted current is given, this current being more potent in producing chemical changes in the system than the interrupted induced current.

It is apparent that two distinct and separate currents, both uninterrupted or both interrupted, or one interrupted and one uninterrupted, can be passed through the patient at the same time and in direction to suit the nature of the case.

What I claim as my improvement, and desire to secure by Letters Patent, is—

1. Constituting the head electrode, C, the terminus of two batteries, which may receive the positive (+) and negative (-) from either battery or instrument, or both of the positives, or both of the negatives, thus completing a double circuit through a single electrode, while the opposite poles of the batteries respectively terminate in traversing electrodes upon the sides of the tub, thus completing the circuit of either or both of the batteries or induced current or currents through any conducting medium placed between them.

2. The traversing electrodes, in combination with conductors placed along the sides of the tub, as and for the purpose specified.

3. Such an arrangement of traversing electrodes that two independent sets of currents can be worked at the same time in the same direction or in opposite directions either longitudinally, transversely, or diagonally through the conducting medium in the tub.

4. Working a primary uninterrupted current in connection with an induced interrupted current, either or both of which may be local or general, combinedly or single, as specified.

5. The adjustable head electrode when constructed and arranged so as to expand and contract their surface, as and for the purpose set forth.

MARK W. HOUSE.
